UNITED STATES PATENT OFFICE.

ARTHUR C. BROWN AND SIDNEY P. SMITH, OF NORWICH, CONNECTICUT.

TOY CAR.

1,381,061.

Specification of Letters Patent.

Patented June 7, 1921.

Application filed May 20, 1920. Serial No. 382,955.

To all whom it may concern:

Be it known that we, ARTHUR C. BROWN and SIDNEY P. SMITH, citizens of the United States, and residents of Norwich, in the county of New London and State of Connecticut, have invented a new and Improved Toy Car, of which the following is a full, clear, and exact description.

This invention relates to a toy car and has 10 for an object to provide an improved construction in which the car body is so mounted on supporting wheels as to not readily tip over when in use.

Another object of the invention is to provide 15 a construction of toy which may be used as a car, and which has the general appearance of an aeroplane, though acting as a car or wagon.

A still further object of the invention is to 20 provide a toy car having a suspension for the body which will not interfere with the turning of the front wheels during steering, and which will allow either front wheel to be raised from the ground without tilting the 25 body and either rear wheel to be raised from the ground without upsetting the device.

In the accompanying drawings—

Figure 1 is a side view of a toy car dis- 30 closing an embodiment of the invention.

Fig. 2 is a top plan view of the structure shown in Fig. 1.

Fig. 3 is a front view of the structure shown in Fig. 1.

Fig. 4 is a sectional view through Fig. 1 on line 4—4.

Fig. 5 is a detail fragmentary perspective view showing a front supporting and steering frame.

Referring to the accompanying drawings 40 by numerals, 1 indicates the body of the car which may be formed of any desired material and of substantially any desired shape, that shown being in the form of a fuselage of an aeroplane when viewed from the side. Viewed from the top it is comparatively narrow, as it is shown as being formed from a wood slab and somewhat pointed at the forward end, which forward end receives a 45 freely rotatable propeller 2 designed to rotate by the air pressure against the same as the car moves along. The rear part of the body 1 is provided with a seat 3 secured in place by nails or other suitable 50 fastening means and arranged to be in a

substantially horizontal plane. Also at the rear is provided a pair of stirrups or bars 4 and 5 bolted or otherwise rigidly secured to the body 1 and provided with apertures at the lower or free ends for receiving a rear 60 axle 6. This axle carries wheels 7 and 8 which freely rotate thereon and which are held in place by any suitable means as by washers and cotter pins. At the front of the body 1 is arranged a frame 9 which supports 65 the front of the body 1 while permitting a free steering action.

As indicated in Figs. 3 and 5 the frame 9 is provided with a yoke member 10 having apertures 11 for accommodating the front 70 axle 12 which axle carries the freely rotatable wheels 13 and 14. The yoke 10 has a central horizontal section 15 which accommodates the screw 16, said screw passing loosely through the section 15 and into the 75 body 1 whereby said body is held in such position as to continually rest upon the section 15. There is enough space or loose motion between the head of the screw 16 and section 15 to allow the yoke 10 to tilt to an appreciable extent without any binding action between the pin 16 and section 15. Riveted or otherwise rigidly secured to the yoke 10, as indicated in Fig. 5, are upright bars 17 and 18, said bars having laterally extending projections 19 and 20 through which screws or other fastening means are passed for clamping a plane or winged surface 21 in place on the extensions 19 and 20. The plane 21 acts as a steering handle for shifting the frame 80 9. A transverse plate or strip 22 is connected to the upright bars 17 and 18 by rivets or in any other suitable way. A slot 23 is arranged in the plate 22, said slot accommodating a pin 24 which extends into the body 95 1 whereby said body is guided and also the frame 9 is prevented from moving away from the body 1 at the upper part of the body. By this construction and arrangement either front wheel may be raised from 100 the ground an appreciable distance without tilting the frame 1 or causing an upsetting action, as the body 1 will automatically maintain a vertical position and the pin 24 will move correspondingly in the slot 23. 105 This construction also permits the easy steering of the car without danger of tilting thereof. In addition the arrangement of the slot 23 and pins 16 and 24 permits either of the rear wheels to be raised from the ground 110

without upsetting the car as the two front wheels would remain on the ground and provide a proper support. This action naturally is a rocking action as far as the front 5 lower surface of the body 1 is concerned as said body rocks on the section 15. In forming the upright bars 17 and 18 of the frame 9 the lower parts thereof are bent outwardly for forming foot rests 25 and 26 so that a 10 child sitting on the seat 3 may have his feet resting on these rests.

We claim:

1. A toy car comprising a body, four traction wheels, a comparatively rigid 15 frame carrying two of said traction wheels adjacent the front of said body, a single lower pivotal pin connecting said body with said frame, a movable connection between the upper part of the body in said frame, 20 said movable connection permitting the frame to swing laterally and means for connecting two of said traction wheels to said body near the rear thereof.
2. A toy car comprising a body, a pair 25 of traction wheels connected to the body at the rear, a frame at the front of said body, a pair of traction wheels for supporting said frame, said frame having a bar on which the front part of said body rests, a 30 pin extending through said bar into the lower part of said body and means connecting the upper part of the body with said frame so as to allow said upper part to swing laterally independently of the frame.
3. A toy car comprising a body, a seat 35 arranged at the rear part of the body, a pair of traction wheels connected with the

rear part of said body, a frame straddling the front part of said body formed with a pair of transverse bars, a pair of traction 40 wheels connected with said frame and a pair of pins extending through said bars into the frame, one pin extending upwardly into the lower part of the body and the other downwardly into the upper part of the 45 body, said last mentioned pin being permitted free side movement so that either of the front wheels may be raised without molesting the vertical position of the body.

4. A toy car comprising a body, a pair 50 of traction wheels connected to the body adjacent the rear, a frame adjacent the front, means for connecting the frame with the body adjacent the front so that the frame may swing freely within certain 55 limits in a plane substantially at right angles to the direction of movement of the car, and a pair of traction wheels connected with said frame.

5. A car of the character described comprising a body, a pair of traction wheels adjacent the rear of the body, a frame straddling the body adjacent the front, said frame having a supporting section and a guiding section, said guiding section having 60 a slide therein, a pair of traction wheels carried by said frame, a pin extending through said supporting section upwardly into the body, and a pin extending through said slot 65 downwardly into the body whereby the 70 frame may tilt without tilting the body.

ARTHUR C. BROWN.
SIDNEY P. SMITH.
